UNITED STATES PATENT OFFICE.

MATTHEW T. CHAPMAN AND MARK C. CHAPMAN, OF AURORA, ILLINOIS, ASSIGNEES TO
THE AMERICAN WELL WORKS, OF AURORA, ILLINOIS, A CORPORATION OF ILLINOIS.

PUMPING MACHINERY.

1,277,382.

Specification of Letters Patent.

Patented Sept. 3, 1918.

Application filed November 8, 1915. Serial No. 60,280.

- To all whom it may concern:
- Be it known that we, MATTHEW T. CHAPMAN and MARK C. CHAPMAN, citizens of the United States, residing at Aurora, in the county of Kane, State of Illinois, have invented certain new and useful Improvements in Pumping Machinery, of which the following is a specification, reference being had to the accompanying drawings.
- 10 Our invention relates to pumping machinery and particularly to the operating mechanism by which a plurality of plunger rods operating single-acting plungers are adapted to be reciprocated. It is one of the objects of our invention to provide new and improved operating means adapted to raise the plunger rods positively, but incapable of forcing the plunger rods on their downward stroke so as to cause them to buckle or break. It is one of the objects of our invention to provide a construction of the type set forth by which two plungers are operated in such a manner as to insure a continuous upward flow of water through 25 the discharge pipe whereby the necessity for overcoming the inertia of alternately stopping and starting the water may be avoided. It is another object of our invention to provide pumping means of this type in which 30 the plunger rods are moved at a constant speed rather than at a constantly-changing speed such as is characteristic of a crank motion. It is another object of our invention to improve devices of this type in sundry details hereinafter pointed out. The preferred means by which we have accomplished our objects are illustrated in the drawings and are hereinafter specifically described. That which we believe to be new 35 and desire to cover by this application is set forth in the claims.
- In the drawings:
- Figure 1 is a side view of our improved pumping mechanism;
- 40 Fig. 2 is a front view of the machine shown in Fig. 1;
- Fig. 3 is a top view of the said machine;
- 45 Fig. 4 is a vertical cross-section through one of the lifting levers, being taken substantially on line 4—4 of Fig. 3;
- Fig. 5 is a vertical cross-section through the lever shown in Fig. 4, being taken substantially on line 5—5 of Fig. 4;
- 50 Fig. 6 is a view showing the construction 55 of a cross-head by the use of which two of the levers are connected with one of the plunger rods, being substantially a vertical cross-section taken on the line 6—6 of Fig. 3;
- Fig. 7 is an enlarged detail, being substantially a vertical cross-section taken on line 60 7—7 of Fig. 6;
- Fig. 8 is an enlarged detail, being a fragmentary cross-sectional view taken on line 8—8 of Fig. 3;
- Fig. 9 is a side view of the plates by 65 which one of the plunger rods is connected with the cross-head;
- Fig. 10 is a view similar in a general way to Fig. 4, but showing a modified form of parts for operating the lever;
- 70 Fig. 11 is a horizontal cross-section taken on line 11—11 of Fig. 10;
- Fig. 12 is another view similar to Fig. 4, but showing a modified form of connections between the lever and the plunger rod;
- 75 Fig. 13 is a side view, partly broken away, showing a modified form of construction by which the forward end of the lever or walking beam is moved vertically at a constant speed on its upward stroke and at a faster constant speed upon its downward stroke;
- 80 Fig. 14 is a top view of the parts shown in Fig. 13, being in part a sectional view taken on line 14—14 of Fig. 13.
- 85 Referring to Figs. 1 to 9, inclusive, in which corresponding parts are indicated by the same reference characters,
- 20 indicates a base of any suitable type built about the upper end of a well tube 21 (see Fig. 2) having mounted thereon a water-discharge head 22 connected with a main or other water pipe 23. Extending downward through the head 22 and through the water-discharge casing 21 are two plunger 90 rods 24—25, the plunger rod 24 being in the form of a tube or pipe with the plunger rod 25 extending therethrough. A stuffing-box 26 of any suitable type surrounds the plunger rod 24 in the upper face of the head 22, serving to prevent the passage of water from the head 22 about the plunger rod. At the upper end of the plunger rod 24 (see Fig. 7) suitable packing 27 is held in position by an adjustable gland 28 about the plunger rod 25.
- 95 100 105 110 115
- 29 indicates a base of any suitable type rising above the base 20, being preferably formed of concrete or cement integrally with the base 20. Mounted upon the base 29 there is a frame 30 comprising standards 31—32 between which is revolubly mounted

a shaft 33. Means is provided for rotating the shaft 33 comprising a gear 34 and a pinion 35, mounted upon a shaft 36 adapted to be driven from any suitable source of power 5 by a pulley 37 mounted thereon.

Revolutely mounted upon the shaft 33 there are a plurality of levers 38—39—40 extending forward from said shaft. In the construction shown in Figs. 1 to 9, each of these 10 levers is in the form of a housing formed of two members 41—42 (see Fig. 4) held together by a plurality of bolts 43. Each of the levers 38—39—40 is provided with a gear 44 revolutely mounted in suitable bearings therein by means of suitable hubs or trunnions 45, as best shown in Fig. 5. Fixed upon the shaft 33, meshing with the gears 44 within the housings formed by the levers 38—39—40, are three pinions 46 by which 15 the gears 44 are adapted to be driven by power from the shaft 33. Each of the gears 44 is provided with a plurality of openings 47, in any one of which a pin 48 is adapted to be placed. Upon the outer ends of the 20 pin 48 of each gear 44 are mounted two links 49, the lower ends of which are pivotally secured in any suitable manner on the frame 25 30, as by a plurality of pins 50, for example.

Each of the pins 48 is limited in its movement to the arc of a circle about one of the pins 50. At the same time the movement of the center of each of the gears 44 is limited to the arc of a circle about the shaft 33. Upon the application of power to the 35 gears 44 through the pinions 46, the levers 38—39—40 are reciprocated up and down about the shaft 33 as a center. Each of the levers 38—39—40 will be in its uppermost position when the center of its pin 48 is between the center of the gear 44 and the center of the pin 50. Each of the levers 38—39—40 will be in its lowermost position when the center of the gear 44 is between the centers of its pins 48 and 50 and in line 40 45 therewith. In the construction shown, the pins 50 are located in such position as to be directly below the centers of the gears 44, or substantially so, at the times when the levers are in their extreme uppermost and lowermost positions. It therefore follows that in the construction shown each of the levers 38—39—40 is moved upward by substantially half of a complete revolution of its gear 44 and is moved downward by the 50 55 other half of the complete revolution.

The arrangement is such, however, that the levers 38—39—40 are given a more rapid downward movement than that of their upstroke, by reason of the fact that the gears 44 are not driven at uniform speed throughout a complete revolution. With one of the pinions 46 being driven at a constant speed in clockwise direction in Fig. 4, the lever shown in said figure will be given a considerably 60 65 more rapid movement on the down stroke

than upon the upstroke, by reason of the constantly changing position of the gear 44 relative to the pinion 46. If the pinion 46 were, during an upward movement of the lever with the links 49 released, given a rotation 70 in clockwise direction in Fig. 4 through an angle equal to that through which the lever was moved, the gear 44 would not be rotated. Upon the basis of the gears 44 having thirty-two teeth, and upon the further basis that 75 the lever is moved during an operative stroke through an angle of forty-five degrees about the shaft 33,—upon such a basis, for moving the lever upward through its stroke of forty-five degrees, with the links 49 connected, the pinion 46 would require such a rotation as to carry twenty teeth successively into mesh with the gear 44, that is to say, sixteen teeth representing one hundred and eighty degrees of the gear 44 and four 80 teeth representing forty-five degrees. For moving the lever through its down stroke, the pinion 46 would require such a rotation as to carry twelve teeth into engagement with the gear 44, that is, sixteen teeth representing one hundred and eighty degrees of the gear minus four teeth representing forty-five degrees of the gear. That is to say, the up stroke of the lever would continue during five-eighths of the period required for a complete revolution of the gear 44 and the down stroke during the remaining three-eighths. 90

As is shown by an inspection of Figs. 1, 2 and 3, each of the levers 38, 39 and 40 is 100 in its intermediate horizontal position, the levers 38 and 39 being in the middle of their upstrokes while the lever 40 is in the middle of its downstroke,—upon the basis of the pulley 37 being driven in counterclockwise direction in Fig. 1. It therefore follows that upon the continued rotation of the pulley 37 in the direction indicated, the lever 40 will complete its downstroke and will start upward while the levers 38 and 105 39 are still moving upward together upon their uncompleted upward stroke. Thereafter the levers 38—39 will complete their upward stroke, move downward through their entire downstroke, and start upward 110 again before the end of the upward stroke of the lever 40 above referred to. 115

Each of the levers 38—39 is provided at its forward end with a groove 51, and the lever 40 is provided at its forward end with two 120 of such grooves 51. As is best shown in Fig. 4, each of the grooves 51 is curved, conforming to the arc of a circle about the axis of the shaft 33. As is best shown in Fig. 2, a cable 52 has its ends attached to the 125 lever 40 at the upper ends of the grooves 51, the said cable being connected with the upper end of the plunger rod 25 by means of a coupling device 53 of any suitable type which will permit the cable 52 to slip longi- 130

tudinally of itself through said connection for maintaining an equality of tension upon the ends of the cable. The ends of a cable 54 are connected with the levers 38-39 at the upper ends of the grooves 51 therein, the cable 54 being connected with the plunger rod 24 by the means hereinafter described.

The means for connecting each of the upper ends of each of the cables at the upper end of its groove 51 comprises a sleeve 55 fixedly secured by any suitable means upon the end of the cable. The sleeve 55 passes through a suitable opening in a plate 56 secured in any suitable manner at the upper end of the groove 51, being adjustably held against withdrawal therefrom by a nut 57 secured by means of screw-threads thereon.

The means for connecting the cable 54 with the plunger rod 24 comprises a cross-head formed of two channel-irons 58-59 having grooved rollers 60-61 revolvably secured between them for engagement with the cable 54. The channel-irons 58-59 are connected to the plunger rod 24 by means of coupling plates 62-63 which embrace the plunger rod above an annular flange 64 thereon, being held against upward movement relative to the rod by means of nuts 65 secured by means of screw-threads upon the rod 24.

Inasmuch as the grooves 51 in the forward ends of the levers 38-39-40 are arc-shaped about the shaft 33 upon which such levers swing, it is evident that at all times the cables 52-54 are maintained constantly in the same vertical plane as the levers are swung up and down, thus providing against any side draft upon the plunger rods 24-25. By reason of the use of the cables 52-54 as connections between the levers and the plunger rods, the plunger rods are insured positive upward movement, while at the same time they are insured against being forced downward by the levers. By the peculiar arrangement of our operating parts the desired lap in the operation of the plunger rods is procured, as above described.

In Figs. 10 and 11 we have shown a modified form of lever and operating parts. In this construction, the lever 66 provided with a groove 51^a is revolvably mounted upon a shaft 33^a between two gears 44^a which are connected together by means of a pin or shaft 67 which is journaled in the lever 66. The links 49^a are secured at their upper ends by means of two separate pins 68-69 to the gears 44^a at one side of the centers of said gears. By the use of the modification here shown the bearing surface between the lever and the gear is very materially reduced.

In Fig. 12, the parts corresponding to those of the structure shown in Figs. 1 to 9 are indicated by the same reference characters, but with the addition of an exponent ^b. In this construction the lever 70 has the end of a cable 71 connected thereto, preferably

by such a device as that shown in Fig. 8. From the lever 70 the cable 71 runs over a pulley 72 revolvably mounted by means of a pin or shaft 73, the cable 71 on the opposite side of the pulley 72 being connected by any suitable means such as 74 with one of the plunger rods. Upon the rotation of the gear 44^b in clockwise direction in said Fig. 12, the forward end of the lever 70 is given a rapid upward movement permitting the plunger 25^b to drop rapidly. The downward stroke of the lever 70 is comparatively much slower whereby the operative upward stroke of the plunger 25^b is rendered enough slower than the downward stroke of such plunger rod as to procure the desired results. Inasmuch as this reversed operation of the lever 70 is procured merely by reversing the direction of rotation of the gear 44^b and the pinion 46^b from that above described in connection with Figs. 1 to 9, it is not believed to be necessary to further describe the operation.

While we have shown the means for maintaining the pins 48 substantially at the same level as the shaft 33 in the form of links 49, it will be understood that we do not wish to be restricted to this particular means nor to the use of the pins 48 at all, except as hereinafter specifically claimed, our invention comprising broadly means having a bearing on the gear 44 eccentrically thereof adapted to move toward and from the axis of the lever, but held substantially against movement in the direction in which the lever is adapted to swing. Neither do we wish to be restricted, except as hereinafter claimed, to having the gears 44 and 46 directly in mesh without the use of auxiliary driving means of suitable type.

So far as we are aware we are the first in the art to provide a pumping mechanism comprising a walking beam, a plunger rod connected with said walking beam, and means for driving said walking beam, independently of the connections between the walking beam and the plunger, comprising a gear carried by the walking beam meshing with the driving pinion about which the gear is movable with the walking beam, and our claims are to be construed accordingly.

In Figs. 13 and 14 we have illustrated a construction comprising cam means which not only serves the purpose of controlling the position of the gear mounted upon the walking beam in lieu of the links 49 of the construction shown in Figs. 1 to 9 for causing a vertical swinging of the lever or walking beam, but also serves to compensate for the irregularity of the vertical movement of the lever. In the construction shown in Figs. 13 and 14 a standard 75 carries at its upper end a shaft 76 upon which is revolvably mounted a two-part lever or walking

105

110

115

120

125

130

beam, the two connected parts 77-78 comprising a lever or walking beam having a cable 79 connected at the upper end of an arc-shaped groove 80. Fixedly mounted upon the shaft 76 is a pinion 81 meshing with a gear 82 revolvably mounted by means of hubs or trunnions 83-84 in a suitable bearing provided by the two-part lever 77-78. The shaft 76 is provided with a 10 driving wheel 85 of any suitable type.

Mounted upon each of the hubs or trunnions 83-84 upon the outer end thereof is a suitable cam 86, being formed integrally therewith or fixed in position thereon by any 15 suitable means. Revolvably mounted below the cams 86 are suitable rollers 87-88 adapted to coöperate with said cams for causing the walking beam to rise upon the rotation of the gear 82 and for controlling 20 the downward movement of said walking beam. The cams 86 are, in the construction shown, laid out to produce movement of the forward end of the walking-beam 77-78 upward at a constant speed throughout 25 its stroke and a subsequent movement of the walking beam downward also at a constant speed throughout the stroke at approximately twice as great a speed, upon the rotation of the driving pinion 81 at a constant 30 speed of rotation in clockwise direction in Fig. 13, this operation being desired under certain circumstances in preference to the constantly-varying speed of movement of the walking-beams of the constructions shown in Figs. 1 to 12.

With the cams 86 causing an upward stroke of one plunger at a constant slow speed and causing a subsequent downward movement of such plunger at a comparatively more rapid speed, and with similarly-arranged cam mechanism causing a like movement of a second plunger, it will be readily understood that upon the proper timing of the cams of one plunger relative 40 to the cams of the other plunger there will be a lap in the movement of the two plungers such as to prevent any stoppage of the water being raised alternately by the upward strokes of the two plungers. By the 45 use of our improved cam mechanism, even when the lap in the movement of the two plungers is comparatively small, the two plungers will upon each upward movement of each plunger have assumed the same 50 maximum rate of upward movement so as to be moving in unison prior to the completion of the upward movement of the plunger nearer the upper end of its stroke.

What we claim as our invention and desire to secure by Letters Patent, is—

1. In a pump, the combination of a plunger rod, a lever provided with bearings spaced apart, a gear revolvably mounted between said bearings on an axis parallel with 65 that upon which said lever is mounted, a

driving gear revolvably mounted on a fixed axis adapted to drive said first-named gear as it moves back and forth with said lever, means connected with said first-named gear eccentrically thereof actuated by the rotation of said gears for giving the lever a vertical reciprocation, and connections between said lever and said plunger rod. 70

2. In a pump, the combination of a plunger rod, a lever in the form of a housing providing bearings in its side walls, a gear revolvably mounted in said housing between said bearings on an axis parallel with that upon which said lever is mounted, a driving gear revolvably mounted on a fixed axis adapted 75 to drive said first-named gear as it moves back and forth with said lever, means connected with said first-named gear eccentrically thereof actuated by the rotation of said gears for giving the lever a vertical 80 reciprocation, and connections between said lever and said plunger rod. 85

3. In a pump, the combination of a plunger rod, a lever provided with bearings spaced apart, a gear provided with trunnions on its side faces adapted to revolve in said bearings on an axis parallel with that upon which said lever is mounted, a driving gear revolvably mounted on a fixed axis adapted to drive said first-named gear as it 90 moves back and forth with said lever, means connected with said first-named gear eccentrically thereof actuated by the rotation of said gears for giving the lever a vertical reciprocation, and connections between said 95 lever and said plunger rod. 100

4. In a pump, the combination of a plunger rod, a lever in the form of a housing providing bearings in its side walls, a gear provided with trunnions on its side faces extending through said bearings for enabling the gear to revolve on an axis parallel with that upon which the lever is mounted, a driving gear revolvably mounted on a fixed axis adapted to drive said first-named gear 105 as it moves back and forth with said lever, means connected with said first-named gear eccentrically thereof actuated by the rotation of said gears for giving the lever a vertical 110 reciprocation, and connections between said lever and said plunger rod. 115

5. In a pump, the combination of a walking beam, reciprocatory pumping means connected with said walking beam, a gear revolvably mounted on said walking beam, a second gear adapted to drive said first-named gear, and means actuated by the rotation of said second gear at a constant speed to cause said first-named gear and said walking beam to be moved upward at a substantially constant speed. 120

6. In a pump, the combination of a walking beam, reciprocatory pumping means connected with said walking beam, a gear revolvably mounted on said walking beam, a 125

second gear adapted to drive said first-named gear, and means actuated by the rotation of said second gear at a constant speed to cause said first-named gear and said walking beam to be reciprocated vertically at substantially constant up and down speeds respectively.

7. In a pump, the combination of a walking beam, reciprocatory pumping means 10 connected with said walking beam, a gear revolvably mounted on said walking beam, a second gear adapted to drive said first-named gear, and means actuated by the rotation of said second gear at a constant 15 speed to cause said first-named gear and said walking beam to be moved upward at a substantially constant speed and to be moved downward in turn at a comparatively more rapid substantially constant speed.

20 8. In a pump, the combination of a walking beam, reciprocatory pumping means connected with said walking beam, a gear revolvably mounted on said walking beam, a second gear adapted to drive said first-named gear, and means acting on said first-named gear eccentrically thereof upon the rotation of said second gear at a constant speed adapted to cause said first-named gear and said walking beam to be moved upward 25 at a substantially constant speed.

9. In a pump, the combination of a walking beam, reciprocatory pumping means connected with said walking beam, a gear revolvably mounted on said walking beam, 30 a second gear revolvably mounted on the axis of said walking beam and adapted to drive said first-named gear, a cam carried by said walking beam, connections between said cam and said gears for rotating said cam, and means cooperating with said cam for causing said walking beam to be reciprocated vertically.

40 10. In a pump, the combination of a walking beam, reciprocatory pumping means 45 connected with said walking beam, a gear revolvably mounted on said walking beam, a second gear adapted to drive said first-named gear, and a cam carried by said first-named gear adapted upon the rotation 50 of said gear to cause the gear and the walking beam to be reciprocated vertically.

11. In a pump, the combination of a walking beam, reciprocatory pumping means connected with said walking beam, a gear 55 having a trunnion revolvably mounted on said walking beam concentrically relative to the gear, a second gear adapted to drive said first-named gear, and a cam mounted on said trunnion adapted upon the rotation 60 of said first-named gear to cause said gear and said walking beam to be reciprocated vertically.

12. In a pump, the combination of a walk-

ing beam, reciprocatory pumping means connected with said walking beam, a gear 65 having trunnions revolvably mounted on said walking beam concentrically relative to the gear, a second gear adapted to drive said first-named gear, cams mounted on said trunnions, and rollers against which said cams bear for causing said first-named gear and said walking beam to be reciprocated vertically upon the rotation of the said gear.

13. In a pump, the combination of a walking beam, reciprocatory pumping means 70 connected with said walking beam, a gear having trunnions revolvably mounted on said walking beam concentrically relative to the gear, a second gear adapted to drive said first-named gear, and cams mounted on said trunnions adapted upon the rotation of said second gear at a constant speed to cause said first-named gear and said walking beam to be moved upward at a substantially constant speed.

14. In a pump, the combination of a walking beam, reciprocatory pumping means connected with said walking beam, a gear having trunnions revolvably mounted on said walking beam concentrically relative to the gear, a second gear adapted to drive said first-named gear, and cams mounted on said trunnions adapted upon the rotation of said second gear at a constant speed to cause said first-named gear and said walking beam to be moved upward at a substantially constant speed and then downward at a comparatively more rapid speed.

15. In a pump, the combination of a walking beam, reciprocatory pumping means 10 connected with said walking beam, a gear having trunnions revolvably mounted on said walking beam concentrically relative to the gear, a second gear adapted to drive said first-named gear, and cams mounted on said trunnions adapted upon the rotation of said second gear at a constant speed to cause said first-named gear and said walking beam to be reciprocated vertically at substantially constant up and down speeds respectively.

16. In a pump, the combination of a walking beam, reciprocatory pumping means connected with said walking beam, a gear having trunnions revolvably mounted on said walking beam concentrically relative to the gear, a second gear adapted to drive said first-named gear, and cams mounted on said trunnions adapted upon the rotation of said second gear at a constant speed to cause said first-named gear and said walking beam to be moved upward at a substantially constant speed and to be moved downward in turn at a comparatively more rapid substantially constant speed.

MATTHEW T. CHAPMAN.
MARK C. CHAPMAN.
